FLYCUTTER FOR CUTTING CIRCLES

Mario Anesi, 4949 Natomo Ave., Chicago, Ill.

Filed July 11, 1962, Ser. No. 70,887

Term of patent 14 years

(Cl. D54—13)

FIG. 1 is an end elevation of a flycutter for cutting circles embodying my design;

FIG. 2 is a side elevation looking at the left side of the cutter as illustrated in FIG. 1;

FIG. 3 is an elevation of the opposite end of the cutter from FIG. 1;

FIG. 4 is a side elevation looking at the right side of the cutter as illustrated in FIG. 1;

FIG. 5 is a top plan view; and

FIG. 6 is a bottom plan view thereof.

The characteristic feature of my design resides in the specific shaped radius bar, having a barrel type blade holder at one end thereof, said radius bar being associated with the body portion in an offset position, all as shown.

The cutting blade and drill are shown in broken lines on the drawing for purposes of illustration only.

I claim:

The ornamental design for a flycutter for cutting circles, substantially as shown and described.
